(57) **CLAIM**

The ornamental design for a solar panel charger, as shown and described.

DESCRIPTION

FIG. 1 is a front perspective view of a solar panel charger, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an enlarged detail view of area 9 in FIG. 2.

The broken lines in the drawings illustrate the portions of the solar panel charger, which form no part of the claimed design.

The dash-dot-dot-dash broken lines in FIGS. 1 and 9 depict the boundaries of the enlarged area and form no part of the claim design.

In FIGS. 1, 2, 3 and 4, the oblique line shading depicts the surfaces of the solar panel charger.
